UNITED STATES PATENT OFFICE.

CHARLES H. CARR, OF PORTSMOUTH, NEW HAMPSHIRE.

SEAM-RUBBER FOR BOOTS AND SHOES.

SPECIFICATION forming part of Letters Patent No. 374,655, dated December 13, 1887.

Application filed October 4, 1887. Serial No. 251,394. (No model.)

To all whom it may concern:

Be it known that I, CHARLES H. CARR, of Portsmouth, in the county of Rockingham, State of New Hampshire, have invented a certain new and useful Improvement in Seam-Rubbers for Boots and Shoes, of which the following is a description sufficiently full, clear, and exact to enable any person skilled in the art or science to which said invention appertains to make and use the same, reference being had to the accompanying drawings, forming part of this specification, in which—

Figure 1 is a side elevation of my improved seam-rubber, some of the parts being shown in section; Fig. 2, an end elevation of the same, some of the parts being shown in vertical section; Fig. 3, a vertical longitudinal section with the standard, bed, and shafts broken off; Fig. 4, a vertical transverse section taken on line $x\ x$ in Fig. 3, and Fig. 5 an elevation of the guide detached.

Like letters of reference indicate corresponding parts in the different figures of the drawings.

My invention relates more especially to means for rubbing down or finishing the seams of boots and shoes; and it consists in a novel construction and arrangement of parts, as hereinafter more fully set forth and claimed, the object being to produce a more effective and otherwise desirable device of this character than is now in ordinary use.

The nature and operation of the improvement will be readily understood by all conversant with such matters from the following explanation.

In the drawings, A represents the bed of the machine, B the standard, and F the arm, these parts being similar in shape to those of a sewing-machine, the standard being secured to the bed A by screws 60. Two circular plates, x , are rigidly secured, by means of screw-bolts z , to the outer end of the arm F, (see Fig. 3,) and are separated by a plate, v , which is provided in its lower portion with a circular opening, t , as shown in Fig. 4. The plates x are provided on their outer edges with flanges m , and disposed on said plates between said flanges and the plate v , so that they will easily revolve thereon, are two rings,

w , having the outer edges of their peripheries serrated to form gears 61, and their inner edges beveled inwardly toward the plate v , as best shown at 62 in Figs. 1 and 3.

A horizontally-arranged shaft, D, has one of its ends journaled in the plates x and its other in the standard B, pulleys E being disposed on said shaft, by means of which the mechanism herein described is driven.

A rubbing or burnishing wheel, H, is secured to the shaft D between the plates $x\ x$ and within the opening t of the plate v . (See Fig. 4.)

A horizontally-arranged shaft, G, is journaled in standards b on the arm F of the standard B. (See Fig. 1.) On the outer end of the shaft G are disposed gears d , said gears being so arranged that their teeth will intermesh with the teeth 61 of the rings w . The shaft G is driven by a worm-gear, K, worm 75, shaft 76, and bevel-gear J, said gear intermeshing with a corresponding bevel-gear, 77, on the shaft D. (See Fig. 1.)

A vertically-arranged rod, f , is fitted to slide in a socket, g , formed in a block, P, secured to the bed-plate A directly under the plates $x\ x\ v$. The rod f is provided with a U-shaped head, h , in which are journaled two bed-wheels, k , by means of stub-shafts i . The wheels k are beveled outwardly on their peripheries, as shown at 80, to correspond with the beveled edges of the wheels $x\ x$, against which they press the leather when in use.

The lower end of the rod f rests on the inner end of a metallic rocking spring, L, a thumb-screw, m , passing through the outer end of said spring into the bed-plate A, by means of which the inner end may be raised or lowered and the tension of the spring registered.

The bed-wheels k are provided with annular rabbets p at their inner edges, which, when united, form a peripheral groove in said wheels, to admit a curved presser foot or bar, R, which extends horizontally under the rubbing wheel H.

The presser-foot R has a vertically-arranged rod or body, which is fitted to slide in the block P in substantially the same manner as the rod f , and its bottom rests upon the inner

end of a similar rocking spring, L^2 , provided with a screw, m^2 , by which its tension can be regulated.

5 A curved seam-guide, T , (see Figs. 4 and 5,) is adjustably secured to the forward edge of the plate v between the plates x x , its lower end extending downward around said plate and close to the presser-foot R . The guide T is provided with two longitudinal slots, 15 and 10 16, through which screws 17 and 18 pass into the plate v , to keep the guide in position thereon.

15 A coiled spring, 21, (see Fig. 5,) is disposed longitudinally in the slot 15, one end of which is secured to the screw 17 and the other to the body of the guide at the lower end of said slot, said spring acting expansively to press the guide downward toward the presser-foot R .

20 The lower end of the guide T is provided with an open slot, 22, (see Fig. 5,) adapted to receive the seam of the boot or shoe upper as it is fed into the machine, a screw, 23, passing transversely through the sides of said slot, 25 by means of which they can be brought or sprung closer together and the slot narrowed when desired.

In the use of my improvement the shaft D is set in motion by means of power applied to 30 the pulleys E , causing the wheel H to be rapidly revolved between the plates x x . As the shaft D revolves, it communicates motion to the shaft G by means of the gears K 77 and the worm 75, revolving the gears d , and there- 35 by setting in motion the rings w w on the plates x x in the direction of their arrow. The friction of the beveled portions of the wheels w upon the bed-wheels k cause them to be revolved inward in the direction of their arrow. By turning in the thumb-screw m and thereby elevating said wheels k the friction between them and the rings w may be increased as desired. The boot or shoe upper is inserted between the wheels k and rings w , 40 with its seam in the slot 22 of the guide T , the under side of said seam resting on the presser-foot R . The rings w feed the upper inward, so that its seam passes directly under the rubbing-wheel H , the pressure of said wheel upon 45 the seam being regulated by means of the presser-foot R , its screw m^2 , and spring L^2 , in a manner that will be readily obvious without a more explicit description.

The rubbing-wheel H is driven at greater 50 speed than the rings w and bed-wheels k , thus thoroughly rubbing and finishing all portions of the seam as it is slowly fed under said wheel.

Having thus explained my invention, what 55 I claim is—

1. In a machine for rubbing the seams of boots or shoes, the body A , provided with the standard B , having the arm F , in combination with the plates x v , secured to said arm, rings 60 w , journaled on the plates x , shaft D , journaled

in the plates x and standard B , rubbing-wheel H , mounted on the shaft D , a presser-foot, bed-wheels, and mechanism for revolving said shaft and wheels, substantially as set forth.

2. In an apparatus of the character de- 70 scribed, the plates x , rings w , journaled on said plates, and the plate v , provided with the opening t , in combination with the gears d , the shaft G , gears K 77, worm 75, shaft D , carrying the wheel H , disposed in said opening, the 75 presser-foot R , wheels k , guide T , and actuating mechanism therefor, substantially as set forth.

3. In an apparatus of the character de- 80 scribed, the rod f , having the U -shaped head h , the beveled wheels k , journaled in said head, and provided with the rabbets p , in combination with the block P , having the socket g , rocking spring L , screw m , and bed-plate A , substantially as set forth.

4. In an apparatus of the character de- 85 scribed, the presser-foot R , having the rod g , in combination with the block P , rocking spring L^2 , screw m^2 , and bed-plate A , substantially as set forth.

5. In an apparatus of the character de- 90 scribed, the presser-foot R , provided with the spring L^2 and screw m^2 , in combination with the shaft D , provided with rubbing-wheel H , rings w , plates x v , bed A , standard B , having 95 the arm F , and mechanism for revolving said wheel, substantially as set forth.

6. In an apparatus of the character de- 100 scribed, the bed-wheels k , rod f , and means for vertically adjusting the same, in combination 100 with the rings w , plates x v , rubbing-wheel H , shaft D , and mechanism for revolving said wheels, substantially as set forth.

7. The improved seam-rubbing machine herein described, the same consisting of the 105 bed A , provided with the standard B , having the arm F , plates x x , secured to said arm and provided with the flanges m , plate v , disposed between the plates x x , and having the opening t , rings w , journaled on the plates x x , and provided with the teeth 61 and beveled portions 62, shaft D , journaled in the plates x x and standard B , and provided with the gear 77 and pulley E , wheel H , disposed on said shaft within the opening t , shaft G , journaled 115 in standards b and provided with the gears d and K , shaft 76, journaled in the arm F and provided with the worm 75 and gear J , block P , secured to the bed A , and having the socket g , rod f , having the head h , bed-wheels k , journaled in said head and provided with the rabbets p , rocking spring L , and screw m , the presser-foot R , adjustably disposed in the block P , the rocking spring L^2 , and screw m^2 , all being constructed, combined, and arranged 120 to operate substantially as set forth.

CHARLES H. CARR.
